UNITED STATES PATENT OFFICE.

HENRY B. HUGHES, OF WICHITA FALLS, TEXAS.

SASH-LOCK.

SPECIFICATION forming part of Letters Patent No. 774,178, dated November 8, 1904.

Application filed May 11, 1904. Serial No. 207,459. (No model.)

To all whom it may concern:

Be it known that I, HENRY B. HUGHES, a citizen of the United States, residing at Wichita Falls, in the county of Wichita and State of 5 Texas, have invented new and useful Improvements in Sash-Locks, of which the following is a specification.

This invention relates to a sash fastener or lock for holding a window-sash, particularly 10 such as are used on railway-cars, at any elevation desired and to lock it against movement from the outside when closed. These 15 objects I accomplish by a simple, cheap, and effective arrangement of parts, easily manipulated and positive in action, the construction and advantages of which are described hereinafter, and clearly set out in the claims.

In the accompanying drawings, Figure 1 is 20 a face view of my improved sash-lock applied to a car-window. Fig. 2 is a detached view of the sash-lock, enlarged, the front plate being removed. Fig. 3 is a perspective view of the operating-lever detached. Fig. 4 is a detail view of a portion of the locking-rack. 25 Figs. 5 and 6 are cross-sectional views on the lines 5 and 6, respectively.

Similar letters of reference indicate the same parts on all the figures.

Referring to Fig. 1, A indicates a window-sash, in this case a car window-sash; B, the window-frame; C, my improved lock screwed to the sash, and D a holding-rack affixed to the window-frame, which also forms a part of my invention. The sash-lock C has the 35 usual box-like casing, having projecting ears c and c^a, through which fastening-screws pass into the sash-frame. Within the casing a cruciform lever E is pivoted at e to a lug c² on the casing, near the bottom thereof and in 40 close proximity to the side c³ nearest the rack D. One arm, E', of the lever E projects laterally through an opening in the side c³ to engage the notches d d' of the holding-rack D. A second arm, E², projects in a substantially 45 horizontal direction opposite that of the arm E' through a slot in the side c⁴ of the casing and is there provided with a finger-piece e', by means of which the lever E is operated. A third arm, E³, rises vertically from 50 the junction of the arms E' and E² to the top

of the casing and carries a finger F, perforated at f. G indicates a curved guide-rod at the top of the casing C, concentric with the pivot e of the cruciform lever E and fastened at each end to the sides c³ c⁴ of the casing or 55 in lieu of the latter side to a bracket c⁵. The curved guide G passes through the opening f in the finger F, between which finger and the bracket c⁵ is placed a coiled spring H, surrounding said guide G, which tends to keep 60 the arm E' always projected and the arm E² in elevated position.

The holding-rack D is preferably formed of three strips of metal cast or bent to form. The central strip D' has notches d d' formed 65 on its forward edge and a flange d² on its rear edge, through holes in which fastening-screws pass to attach the holding-rack to the window-frame. Riveted to the central strip D' are strips D² D³, one on either side, the strips being flanged at their forward edge, as shown. The face of the casing C next the window-sash is extended beyond the side c³ for a short distance and then turned inwardly to form a narrow flange c⁶, between which and the side c³ a 70 guideway is formed in which the flange on the strip D² enters and slides as the sash is raised and lowered. The notches d on the strip D' have flat upper edges joined by inclined front edges, forming shoulders d³, on which the arm 75 E' rests to hold the window-sash in elevated position. The lowest notch d' is, however, of substantially rectangular form, which when the window is lowered and the arm E' enters 80 said notch locks the window closed.

To raise the window from a closed position, the finger-piece e' is depressed to operate the cruciform lever E. This movement withdraws the arm E' from the notch d' and compresses the spring H. The window-sash can 85 now be raised to any height desired and held open by the arm E' engaging one of the shoulders d³. The window-sash may be raised higher by simply lifting it, the lever E yielding, as readily understood; but to lower the 90 sash the finger-piece must be depressed and so held until the window falls to the position desired. If dropped to the bottom, the arm E' will enter the notch d' and lock the window, 95 as heretofore stated.

While I have shown a curved guide surrounded by a spiral spring, this arrangement is not an essential feature, as a spring of other form and differently placed may be substituted for the spiral spring, while the finger F may be made sufficiently wide to bear against the cover-plate of the casing.

Having thus described the invention, what is claimed as new is—

- 10 1. In a sash-lock, the casing, combined with a pivoted cruciform lever therein, having a locking-arm and an operating-arm projecting through opposite sides of the casing, an upright arm having a finger, a guide, and an operating-spring.
- 15 2. In a sash-lock, a casing, a pivoted cruciform lever therein having locking and operating arms projecting through opposite sides of the casing, and having an arm provided

with a perforated finger, a curved guide-rod 20 extending through the perforated finger and being concentric with the pivot of the lever, and a coiled spring surrounding the curved arm and bearing against the finger.

3. In a sash-lock, a casing having a flanged 25 projection thereon, a cruciform lever pivoted within said casing and having a locking-arm and an operating-arm, combined with a rack having holding-notches and a single locking-notch, and a flange adapted to engage the 30 flanged projection on said casing.

In testimony whereof I affix my signature in presence of two witnesses.

HENRY B. HUGHES.
